US00D977325S

(12) **United States Design Patent** (10) **Patent No.:** **US D977,325 S**
(45) **Date of Patent:** **** Feb. 7, 2023**

(54) **HANDLE**

(71) Applicant: **Benoit Rolland**, Watertown, MA (US)

(72) Inventor: **Benoit Rolland**, Watertown, MA (US)

(73) Assignee: **Benoit Rolland**, Watertown, MA (US)

(**) Term: **15 Years**

(21) Appl. No.: **29/808,674**

(22) Filed: **Sep. 22, 2021**

Related U.S. Application Data

(63) Continuation of application No. 29/772,378, filed on Mar. 1, 2021, now Pat. No. Des. 934,051, which is a continuation of application No. 29/610,721, filed on Jul. 14, 2017, now abandoned.
